UNITED STATES PATENT OFFICE.

GEOERGE N. MAS, OF WASHINGTON, DISTRICT OF COLUMBIA.

DESIGN FOR A BOTTLE.

Application filed May 29, 1925. Serial No. 13,589. Term of patent 14 years.

To all whom it may concern:

Be it known that I, GEORGE N. MAS, a citizen of the United States, residing in the city of Washington, District of Columbia, have invented a new, original, and ornamental Design for Bottles, of which the following is a specification, reference being had to the accompanying drawing, forming part thereof.

The figure shows a view in elevation of a bottle embodying my design.

I claim—

The ornamental design for a bottle, substantially as shown.

GEORGE N. MAS.
